Primary Examiner — Kevin K Rudzinski

(74) Attorney, Agent, or Firm — Steven A. Nielsen; www.NielsenPatents.com(57) CLAIM

The ornamental design for a shower body wrap towel, as shown and described herein.

DESCRIPTION

FIG. 1 is a top view of a shower body wrap towel showing my new design; and,

FIG. 2 is a bottom view thereof.

The broken lines shown in the drawings illustrate stitching and form part of the claimed design.

1 Claim, 2 Drawing Sheets
